United States Patent Office

Des. 216,895
Patented Mar. 17, 1970

216,895

FRATERNAL STANDARD OR THE LIKE

George M. Wallace, 64 Clinton St.,
Paterson, N.J. 07501

Filed May 19, 1969, Ser. No. 17,215

Term of patent 14 years

Int. Cl. D11—99
U.S. Cl. D29—23

FIGURE 1 is an elevation of a fraternal standard or the like showing my new design;

I claim:

The ornamental design for a fraternal standard or the like, as shown.
